RIVETING TOOL FOR SICKLES

Lloyd T. Smith, Newton, Kans., assignor to Rains Manufacturing Company, Inc., Harvey County, Kans., a corporation of Kansas

Filed Nov. 21, 1963, Ser. No. 77,533

Term of patent 14 years

(Cl. D54—10)

FIG. 1 is a plan view of a riveting tool for sickles, showing my new design;

FIG. 2 is a side elevational view thereof;

FIG. 3 is a detail fragmentary cross sectional view taken on line 33 of FIG. 2 thereof; and

FIG. 4 is a detail fragmentary cross sectional view taken on line 44 of FIG. 2 of riveting tool for sickles.

I claim:

The ornamental design for a riveting tool for sickles, as shown.
